LIGHTING FIXTURE

William F. Little, Yonkers, N. Y., assignor to
 Electrical Testing Laboratories, New York,
 N. Y., a corporation of New York

Application September 13, 1938, Serial No. 229,654

2 Claims. (Cl. 240—78)

The present invention relates to lighting fixtures, and is more particularly directed toward lighting fixtures designed for mounting close to the ceiling over dining-room tables and the like.

The present invention contemplates a lighting fixture for this purpose adapted to use a single pendent lamp with a mirrored lower hemisphere, a single enclosing bowl with low transmission and high transmission zones associated with the reflector for directing a substantial amount of the light toward nadir.

The accompanying drawing shows, for purposes of illustrating the present invention, one embodiment in which the invention may take form, it being understood that the drawing is illustrative of the invention rather than limiting the same.

In this drawing:

Figure 1 is a side elevational view with parts in section; and

Figure 2 is a sectional view at an enlarged scale.

A ceiling supported lamp socket is indicated at 10 and a concentric sheet metal band at 11. The socket supports a pendent lamp 12 having its lower hemisphere mirrored or coated, as indicated by the stippling 13. The band 11 carries three shade supporting screws 14 adapted to enter a bead 15 about the upper edge of a translucent bowl 17. This bowl may conveniently be made of glass and has an upper curved portion 18 of high diffusion and lower transmission and intermediate substantially horizontal portion 19 which is preferably lightly etched and therefore of high transmission, and a bottom hemispherical portion 20 of low transmission.

The curvature of the portion 18 is preferably such that it merges with the shape of the metal band 11 to provide a continuous curve up to the ceiling line. The high transmission zone 19 is at the level of the light source in the lamp 12 and supports a substantially conical reflector 21. This reflector intercepts the direct light from the source and much of the reflected light from the lamp coating and reflects this light down through the high transmission zone 19 for illuminating objects directly below. As this is a harsh light

with very slight diffusion it produces bright reflected images in dishes, silverware, glasses and the like on the table directly below the lighting unit.

The low transmission or high diffusion zones may be provided by enameling glass, or in any other suitable way, and they receive a small amount of light which first escapes up through the opening in the reflector 21 and is then scattered about inside the unit.

It is apparent that, within the scope of the invention, modifications and different arrangements may be made other than is herein disclosed, and the present disclosure is illustrative merely, the invention comprehending all variations thereof.

What is claimed is:

1. A lighting fixture comprising a pendent lamp, a bowl having a high transmission, substantially horizontal zone at the height of the light center of the lamp, a low transmission zone extending downwardly from the inner edge of the horizontal zone and disposed about the bottom of the lamp, and a low transmission zone extending upwardly and outwardly from the periphery of the high transmission zone, and a reflector disposed above the high transmission zone to screen the upwardly and outwardly extending zone and reflect upwardly directed light down through the high transmission zone.

2. A ceiling lighting fixture, comprising a supporting band secured to the ceiling with its inner edge below the ceiling line, a centrally disposed pendent lamp having a mirror coating on the lower hemisphere, a light diffusing bowl having an upper portion which is downwardly convex and of low transmission, a flat high transmission zone at the bottom of the low transmission zone and at substantially the height of the light source of the lamp, and a hemispherical bottom portion of low transmission, an annular downwardly and outwardly flaring reflector for directing light out through the high transmission zone, and bowl securing means carried by the band.

WILLIAM F. LITTLE.
